(57) **CLAIM**

The ornamental design for a paint brush handle, as shown and described.

DESCRIPTION

FIG. 1 is a perspective view of a paint brush handle showing my new design;

FIG. 2 is a right side elevational view thereof;

FIG. 3 is a left side elevational thereof;

FIG. 4 is a rear elevational view thereof;

FIG. 5 is a front elevational view thereof;

FIG. 6 is a top plan view thereof; and,

FIG. 7 is a bottom plan view thereof.

The broken lines shown in the drawing figures illustrate elements of the article of manufacture that form no part of Applicant's claimed invention.
